COMMERCIAL PACKAGE

John J. Lescher, New York, N. Y., assignor to
Blythe Johnson, New York, N. Y.

Application February 27, 1935, Serial No. 8,539

2 Claims. (Cl. 229—51)

This invention relates to commercial packages, and has for a particular object the provision of an improved cigarette package.

It is an object of this invention to provide an improved package which may be conveniently opened without any difficulty whatsoever and without destroying the body portion of the package which continues to serve as a protection for the contents of the package.

10 A further object is the provision of an improved package opening at the top and so constructed that the whole top or only a portion of the top may be readily removed without mutilating the body portion of the package, but after the top 15 has thus been removed it can not be replaced, thereby preventing fraudulent filling of the package or a removal or substitution of the contents without the knowledge of the purchaser.

With these and other objects in view, reference 20 should be had to the accompanying drawing, in which:

Fig. 1 is a perspective view of a cigarette package embodying features of the present invention;

Fig. 2 is a view similar to Fig. 1 with a portion 25 of the top removed;

Fig. 3 is a perspective view of the portion of the top which has been removed from the package in Fig. 2;

Fig. 4 is a sectional view in the direction of the 30 arrows on the line 4—4 in Fig. 1; and

Fig. 5 is a plan view of a blank provided with suitable folding lines and weakened lines which may be used in making the package shown in Figs. 1 through 4.

35 In the accompanying drawing, the invention is illustrated as being applied to a commercial package for cigarettes, to which my invention has particular application. However, it is to be understood that it may be used in association with other types of commercial packages.

The cigarette package illustrated is of usual construction, being formed of a blank 10 preferably composed of two layers, an outer layer of foil 11 and an inner layer of paper 12. The blank 45 is provided with vertical fold lines 13, horizontal fold lines 14 adjacent the top and bottom, and with diagonally disposed fold lines 15 at the two ends. When folded along these lines a package is provided having front and rear panels 16, side 50 panels 17, a top portion 18, and a bottom 19. Spaced a short distance from the horizontal fold line 14 near the upper end of the package is a weakened or perforated line 20 which extends around the front, back and one side of the pack- 55 age.

A generally loop-shaped severed line 25 demarking the handle tab 26 communicates with the weakened line 20 and extends across the remaining side of the package. Another weakened or perforated line extends across the top of the package and communicates with the weakened line 20 at a point on each side of the package. This weakened line is preferably disposed nearer the side of the package where the tab 26 is formed, and in the package illustrated in the accompanying drawing the last mentioned weakened line is made up of the two perforated lines 21 extending from the line 20 to the edge of the blank, each of the lines 21 being spaced an equal distance from the horizontally disposed fold lines 13 at the side of the package.

When the blank 10 is folded along the vertical, horizontal and diagonal fold lines to provide a package as shown in Fig. 1 of the drawing, it will be seen that the perforated line 20 extends substantially the entire distance around the top of the package, while the severed line 25 extends the remaining distance providing a handle tab 26 at one side of the package and integral with the top. The second perforated line 21 will then extend across the top of the package connecting two points on the first perforated line. A paper label 22 is then preferably secured around the outside of the package and a seal or revenue stamp 23 may be glued over the top of the package. The label 22 is preferably provided with a cut-out portion 24 on the side where the tab 26 is provided, so as to facilitate both the opening of the package and the removal of cigarettes after the package has been opened. The tab 26 may be disposed inside of the outer wrapping label 22 as shown or, if desired, the tab may be permitted to extend outside of the label 22 so that it may be more conveniently positioned for opening the package.

To open the package the tab 26 is grasped between the thumb and forefinger and raised upwardly, severing the top from the package along the perforated line 20. By guiding the direction of the tear with the other hand the top may be 45 completely removed by permitting the tearing to continue along the line 20 while only a portion of the top may be removed by directing the direction of force along the weakened line 21. When the top or a portion thereof has been removed, as shown in Fig. 2, due to the cut-out portion 24, it will be seen that the cigarettes inside of the package may be readily removed.

From the foregoing it will be seen that an improved commercial package has been provided,

which may be conveniently opened without mutilating or destroying the body of the package itself, and which can not be resealed without detection by the purchaser.

5 It is to be understood that modifications may be made in the illustrated and described embodiment of the invention, such as forming the cut-out portion 24 in the outer label so as to conform with the tab 26 at the side of the package.

10 I claim:

1. A commercial package for cigarettes including side, bottom and top portions, said package being provided with a weakened line extending almost completely around the top of the package, 15 a severed line extending the remaining distance around the top, and a weakened line extending across the top of the package and connecting two

points on the first mentioned weakened line, said severed line being formed so as to provide a handle tab integral with the top of the package.

2. A commercial package for cigarettes including front, rear, side, top and bottom portions, a 5 weakened line extending around the front, rear and one side of said package adjacent the top, a generally U-shaped severed line formed in the other side portion of the package and communicating at its two ends with the weakened line, 10 and a second weakened line extending across the top of the package and connecting two points on the first mentioned weakened line, said severed line being formed so as to provide a downwardly depending handle tab at the side of the package 15 integral with the top.

JOHN J. LESCHER.
